UNITED STATES PATENT OFFICE.

WILLIAM H. PERRY, OF CONCORD, NEW HAMPSHIRE.

DESIGN FOR A MONUMENT.

SPECIFICATION forming part of Design No. 23,364, dated June 12, 1894.

Application filed May 14, 1894. Serial No. 511,253. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing; and I do hereby declare the following to be a full, clear, and exact description of the invention, such as will enable others skilled in the art to which it appertains to make and use the same.

In the accompanying drawing I use figures and letters of reference to designate the different features of my design, and the style of finish.

The base 1, is oblong, having four vertical sides terminating in an obtuse frustum of a pyramid 2. The pedestal is also oblong and has four vertical sides 3, which terminate in an acute frustum of a pyramid 4. Upon one or more sides of the pedestal is formed a tablet 5, which has the appearance of being in relief, and may be so termed because of a rectangular groove 6, which completely surrounds it. The side or sides of the pedestal in which is formed the tablet 5 will be provided with an upward projection 7, the top of which inclines inward and upward to meet the frustum 4, and said projection will have vertical ends 8. The oblong shaft has four vertical sides 9, which are ornamented with tablets 10

and 11;—the former being rectangular, as shown by the border lines 12, and the latter, 35 on the longest sides of said shaft, being of the configuration shown by the border line 13. A cap 14, is mounted on the top of said shaft, the sides of which project, the lower edges of said projection being beveled as at 15, and 40 their upper edges being slightly curved or arched as shown at 16, and unite with the obtuse frustum of a pyramid 17, which forms the top of the cap 14. The sides of said cap are provided with raised tablets 18 the lower edges 45 of which are formed of irregular scallops 19 having for ornamentation one or more tassels 20, pendent from between the scallops. The frustum 17 of said cap will be ornamented with the tablets 21, on its sides and the tablet 50 22, on its top.

The monument will be ornamented by a finish for the various parts of a different character, which are designated by reference letters,—A, representing polished work, B, ham- 55 mered work and, C, rock-work.

Having set forth the peculiar features of my design, what I claim is—

The design for a monument substantially as herein shown and described. 60

In testimony whereof I affix my signature in presence of two witnesses.

WILLIAM H. PERRY.

Witnesses:

J. B. THURSTON,
CARRIE E. EVANS.
